ELECTRICAL TESTING APPARATUS

Joseph A. Mas, Woodbury, N.Y., assignor to Dynamic Instrument Corporation, Plainview, N.Y., a corporation of New York

Filed Mar. 2, 1966, Ser. No. 1,256

Term of patent 14 years

(Cl. D26—1)

FIGURE 1 is a front view of the electrical testing apparatus in accordance with the invention.

FIGURE 2 is a rear view of the design shown in FIGURE 1.

FIGURE 3 is a top view of the design shown in FIGURE 1.

FIGURE 4 is a side view of the design shown in FIGURE 1.

FIGURE 5 is a bottom view of the design shown in FIGURE 1.

The essential features of the design reside in the full line portions of the drawing.

I claim:

The ornamental design for an electrical testing apparatus, as shown and described.
